(57) **CLAIM**

The ornamental design for a food storage container, as shown and described.

DESCRIPTION

FIG. 1 is a top perspective view of a food storage container showing our new design;

FIG. 2 is a bottom perspective view thereof;

FIG. 3 is a top view thereof;

FIG. 4 is a bottom view thereof;

FIG. 5 is a side view thereof;

FIG. 6 is an exploded view thereof;

FIG. 7 is a bottom perspective view thereof;

FIG. 8 is a top view thereof;

FIG. 9 is a bottom view thereof; and,

FIG. 10 is a side view thereof.

The broken lines illustrate portions of a food storage container and form no part of the claimed design.

1 Claim, 8 Drawing Sheets
